CLAIM

The ornamental design for a filter for rain spout, as shown.

DESCRIPTION

FIG. 1 is a front plan view of the filter for rain spout of the present invention;

FIG. 2 is a back plan view of the filter for rain spout of FIG. 1;

FIG. 3 is a left side plan view of the filter for rain spout of FIG. 1;

FIG. 4 is a right side plan view of the filter for rain spout of FIG. 1;

FIG. 5 is a top plan view of the filter for rain spout of FIG. 1;

FIG. 6 is a bottom plan view of the filter for rain spout of FIG. 1; and,

FIG. 7 is a cross sectional view along line 7—7 of FIG. 5 of the filter for rain spout of FIG. 1.

The claimed design is shown fragmented to indicate indeterminate length.
